UNITED STATES PATENT OFFICE.

DAVID J. STEPHENSON, OF PORT HURON, MICHIGAN.

AUTOMATIC ADVERTISING DEVICE.

SPECIFICATION forming part of Letters Patent No. 317,240, dated May 5, 1885.

Application filed January 25, 1884. (No model.)

To all whom it may concern:

Be it known that I, DAVID J. STEPHENSON, of Port Huron, in the county of St. Clair and State of Michigan, have invented new and useful Improvements in Automatic Advertising Devices; and I do hereby declare that the following is a full, clear, and exact description thereof, reference being had to the accompanying drawings, which form a part of this specification.

This invention relates to certain new and useful improvements in the construction of advertising-clocks of that class which automatically and intermittently expose business-cards through an opening for the purpose in the door of the clock.

The invention consists in the peculiar construction of the various parts, their combination, and operation, as more fully hereinafter described, and particularly pointed out in the claims.

Figure 1 is a front elevation of the clock and its attachments with the clock-door open. Fig. 2 is a detached detail showing the connection between the clock-train and the shaft which carries the cards.

In the accompanying drawings, which form a part of this specification, A represents a clock-case provided with a door, B, and within this case is laterally journaled the two shafts C and D, around which, upon suitable drums, E, on each shaft, is carried the endless belt F, which is divided into equal spaces of equal length. The drums are rectangular in form, each face thereof being equal to one of the divisions of the endless belt, and the endless belt is made of thin sheets of metal in sections properly hinged together, such hinges or connections being so made as to form clips upon the front face of each to hold cards for advertising purposes, and readily allow the same to be removed and changed when necessary. Upon the shaft D is the pinion G, driven by the cog-wheel H, which is suitably journaled, and which is driven by a spring, I, inclosed within the case or drum I, which spring is wound up through the key-hole J. Upon the opposite end of this shaft D is secured a scape-wheel, K.

L is the hour-wheel or minute-wheel of the clock-train proper, carrying the cam M, which in its rotation causes the lever N, carrying the pallets O and P, to control the intermittent

movement of the scape-wheel K, and limit it to four stoppages in each revolution of the shaft D. The front face of this scape-wheel is provided with a series of pins, r, or their equivalent, which in the intermittent rotation of such scape-wheel rings the bell in the following manner: A crank-lever, S, supported in suitable bearings, carries a hammer at its upper end and has a bent portion, s, at its lower end, which bent portion is set so as to be between the bearings in which the shift-lever S turns, and the scape-wheel K, so that when one of the pins r comes in contact with the bent portion s it moves it until it assumes the position shown in dotted lines, when the spring S' causes it to return to its normal position, thus giving a vibratory movement to the crank-lever S, by means of which the bell T is rung at each movement of such scape-wheel.

U is an aperture through the door of the clock, preferably covered with glass, through which the cards upon the endless belt are intermittently exposed by the intermittent rotation of the shaft D, through the means hereinbefore described.

What I claim as my invention is—

1. The shaft D, rotated by a spring movement, and the endless chain F, supported and impelled thereby, in combination with a clock and a clock-case, the scape-wheel K, secured directly to said shaft, the cam M, and the three-armed lever N O P the arm N operated by said cam, and the arms O P, operating on said scape-wheel to automatically regulate the movement of said shaft, substantially as and for the purpose set forth.

2. The advertising device herein shown and described, consisting of the shaft D, endless chain F, supported and impelled thereby, scape-wheel K, secured to said shaft and provided with pins r upon its front face, wheel L, carrying cam M, lever N, carrying pallets O and P for controlling the intermittent motion of said scape-wheel, and the crank-lever S, having bent portion s, in combination with a clock and a clock-case, as and for the purposes set forth.

DAVID J. STEPHENSON.
